UNITED STATES PATENT OFFICE.

WILLIAM H. McGREW AND CHARLES A. CLARK, OF ST. LOUIS, MISSOURI.

IMPROVEMENT IN SELF-CLOSING PITCHERS.

Specification forming part of Letters Patent No. 170,096, dated November 16, 1875; application filed October 6, 1875.

To all whom it may concern:

Be it known that we, WILLIAM H. McGREW and CHARLES A. CLARK, both of the city and county of St. Louis and State of Missouri, have invented a new and useful Improvement in Self-Closing Beer-Pitchers, which improvement is fully set forth in the following specification, reference being had to the accompanying drawings:

Our invention consists in a pitcher which is hermetically closed at top, and which is filled and emptied only through the spout, which is made circular, and supplied with a spring plug or valve, of which it forms the seat. The valve-stem extends through the side of the pitcher beneath the handle, where it has an eye, through which a finger is inserted to draw back the plug, the plug being forced into the spout by a spring.

The drawing shows a longitudinal vertical section, with the part beyond the section plane in perspective.

A is the pitcher, having a handle, B, and a tubular spout, C. D is the top, hermetically cemented in place. The top D is preferably of glass. The inner end of the tubular spout forms the seat of the valve-plug E. This plug is preferably made of caoutchouc or other soft substance. F is the valve-stem, extending through the back of the pitcher, and ending at the rear in an eye, G, into which the finger is inserted to open the valve. The stem passes through a guide-bar, H, whose ends rest in small recesses *h* inside the pitcher, beneath the top. The stem has a fixed collar, I, against

which the front end of the spiral spring J presses. This spring surrounds the stem, and its rear end presses against a loose washer, K, on the stem, and this washer is thrust by the spring against the washer of caoutchouc or leather, through which the stem passes, the arrangement being such as to make a close joint where the stem passes through the pitcher, to prevent the escape of gases from the beer, the valve preventing their escape through the spout, except when drawn back to permit the liquor to be poured in or out.

In filling the pitcher, it is held with the spout upward, and in connection with the faucet, and the valve is held open. When sufficiently filled the valve is allowed to close, which it does under the action of the spring J, and the contents may be kept fresh for a long time, as the gases are not permitted to escape.

In pouring out the beer, the valve is drawn back. No gases escape, except those mixed with the liquid, as the latter covers every part of the valve-opening, and the gases above the beer do not come in contact with the opening.

We claim as our invention—

The combination, in the pitcher, of the close top D, tubular spout C, and spring-valve E F J, substantially as set forth.

WILLIAM H. McGREW.
CHAS. A. CLARK.
